MOP SHAKING DEVICE

Jules J. Brell, New York, N. Y., assignor of one-third to Harry Radzinsky, New York, N. Y.

Application July 19, 1933, Serial No. 681,156

8 Claims. (Cl. 15—118)

This invention relates to an improvement in mops, and particularly to dust mops or like articles.

Dust or dry mops are usually cleaned by being vigorously shaken, it having been found that this is apparently the only simple method by which the body of the mop may be effectively ridden of the accumulated dust and dirt picked up during the dusting operation. The fastidious housewife usually shakes the mop vigorously upon a sheet of newspaper to collect the dust and dirt and then destroys the paper and its contents. Some shake the mop into a receptacle, while others pursue the unsanitary practice of shaking the mop out of a window, this latter practice being that most generally followed due to the difficulty of shaking the mop vigorously enough to rid it of its dirt and dust while holding it positioned over a piece of paper or in a receptacle.

The object of this invention is to provide a means by which the mop may be vigorously vibrated or shaken so that its accumulated dust and dirt may not only be dislodged but may easily be directed into a receptacle or on a piece of paper which may be gathered up with its contents and destroyed.

A further object of this invention is to provide a mop shaking device of the character described which will be so constructed that when it is applied to a reversible or two-sided mop, both sides of the mop may be freely used without interference from the mop shaking mechanism.

A further object of the invention is to provide a mop shaking device in which the co-operating elements constituting the actuating means will be effectively enclosed or concealed so that no projections or other parts likely to damage furniture or woodwork during the cleaning operation will be exposed on the mop or on its handle.

The invention contemplates a means by which a very vigorous shaking or vibrating motion may be applied to the mop head to cause it to swing with a rapid, oscillating motion about its pivotal connection with the mop stick. This rapid, rocking motion easily and effectively shakes the dust and dirt from the mop strands, and if the mop is held over a receptacle or piece of paper during the shaking operation, the dirt and dust dislodged thereby can be readily directed into the receptacle or on the paper.

In the accompanying drawings, Fig. 1 is a vertical sectional view of a mop provided with a shaking device constructed in accordance with this invention; Fig. 2 is a transverse sectional view through the mop and the handle socket there-

for; Fig. 3 is a sectional view on the line 3—3 of Fig. 2, looking in the direction of the arrows; Fig. 4 is a sectional view on the line 4—4 of Fig. 1, looking in the direction of the arrows; Fig. 5 is a sectional view on the line 5—5 of Fig. 1, looking in the direction of the arrows; Fig. 6 is a vertical sectional view through the main pulley mounted on the mop frame; Fig. 7 is a view of a modified structure; Fig. 8 is a diagrammatic view of the lower part of the mop-acutating cable showing how it is looped about the lower pulley and Figs. 9 and 10 are views illustrating how the mop is swung during the shaking operation, or to face either of the two faces of the mop toward the floor.

The device constituting the invention may be applied to almost any of the well-known types of mop and in the embodiment of the invention shown in Figs. 1 to 6 inclusive, the mop there shown is provided with a backbone or frame 8 made of spiralled or twisted wire, formed with a series of undulations as indicated in dotted lines in Fig. 2. The mop strands 9, constituting the body of the mop, are held between the twisted wires in the manner common to mop construction. The type of mop shown is a reversible one. That is to say, either side of the mop is adapted to be used in contact with the floor. The ends 10 and 11 of the backbone or frame 8 of the mop are joined by welding or the like with the shaft 12 which, after the welding operation, becomes an integral part of the frame or backbone 8 so that the same is then in the form of a continuous loop as clearly shown in Fig. 3. Pivoted on the shaft portion 12 of the frame is a housing 13 composed of two halves connected and held together by means of the screw 14. The housing is provided with an upwardly extending tubular portion 15 which constitutes a socket for the reception of the lower end of the mop stick or handle 16 held within the socket 15 by means of screws or rivets 17.

Fixed on the shaft portion 12 of the frame is a pulley 18 about which a flexible cable 19, preferably of wire, extends. The cable makes approximately one and one-half turns around the pulley as shown in Fig. 8 and is secured to the pulley by means of a fastening member such as the staple 20 shown in Figs. 6 and 8. After passing around the pulley, the cable extends upwardly and operates against idle rollers 21 and 22, also located within the housing 13, and mounted to rotate on shafts 23. The rollers 21 and 22 are free to move laterally on their shafts 23 so as to maintain a constant contact with the cable 55

19. The cable extends upwardly from the pulleys 21 and 22 and has its two upwardly extending portions positioned in the longitudinal parallel grooves 24 located in the mop handle 5 so that the cable is practically concealed and no parts of it project outside of the face of the mop handle.

Near its upper end, the mop handle is provided with a transverse slot 25 in which a pulley 26 is rotatably mounted on the shaft 40. The cable 19 extends over the pulley and has its ends secured at 27 and 28 to a tubular sleeve 29 surrounding the mop handle and slidable thereon. When the sleeve 29 is reciprocated or slid up and down on the mop handle it will draw the cable 19 back and forth over the pulley 26, and since the cable is secured to the pulley 18 fixed on the mop frame, it will cause the mop to be rocked. The cable is provided with a take-up spring 30 which holds it constantly taut, and stops or bumpers 31 and 32 are provided on the mop handle to limit the sliding movement of the sleeve 29 in both directions. These bumpers incidentally impart a shock or thump to the mop at each end of the stroke of the sleeve, such shock or thump acting to dislodge dust or dirt from the mop during the shaking operation.

With the device described, all of the parts of the shaking apparatus are completely enclosed and in no manner add bulk or produce protuberances on the mop which would be likely to damage furniture or woodwork during the dusting operation. The device is so constructed that the mop can be swung about a 180° arc to present either its top or bottom surface against the floor so that it is applicable to a reversible mop of the kind shown herein, or to any other similar kind.

In Fig. 9 the mop is shown as it is held in the hands in readiness for the shaking operation. It will be there seen that one hand grasps the mop stick, while the sleeve 29 is held in the other hand. In Fig. 9, the face 46 of the mop, shown uppermost in Fig. 1, is shown facing the floor, and at this time the sleeve 29 is in its raised position or in other words in contact with the upper bumper 31. To reverse the mop, or direct the face 41 toward the floor, it is merely necessary to push the sleeve 29 downwardly until it comes into contact with the lower bumper 32. This movement of the sleeve swings the mop through an arc of at least 180°, or to the position shown in Fig. 10 where it will be seen that the face 41 of the mop is directed toward the floor. By sliding the sleeve rapidly backward and forward within the space between the two bumpers 31 and 32, the mop is vibrated or shaken and the dust and dirt dislodged from it. By merely moving the sleeve 29 upward or downward as required either side of the mop may be presented against the floor as no parts of the shaking device protrude to prevent this. It may be applied with equal facility to a non-reversible mop.

The structure shown in Fig. 7 is similar in every way to the device herein described, except that instead of a pulley 18 being used on the shaft portion 12 of the mop frame, a two-armed lever 33 is used on the shaft portion 12. This arrangement is applicable only in connection with one-sided mops, since it does not permit a 180° swinging movement or complete reversal of the mop.

To use the device, it is merely necessary to hold the mop over a receptacle or piece of paper

and grasping the sleeve 29 in one hand and a part of the handle in the other, the sleeve is vigorously reciprocated, this action causing the mop to be rocked or vibrated on its axis 12 so that the dust and dirt accumulated by the cleaning operation is shaken loose and deposited in the receptacle or on the paper. The stops or bumpers 31 and 32 are preferably made of rubber or some other like material so that the shaking operation is relatively noiseless and extremely effective.

What I claim is:

1. A device of the class described comprising, a reversible mop having two mopping surfaces on two of its opposite sides and adapted for use with either of its two mopping surfaces downwardly disposed, a mop frame, a handle pivoted on one side of said frame, a slidable element mounted on the handle for movement with respect thereto, a rocking member secured to the mop, and means connecting the rocking member and slidable element to cause the mop to be rocked with respect to the handle by movement of the sliding element, to an extent necessary to bring either one of the two mopping surfaces of the mop downwardly disposed to mopping position.

2. A device of the class described comprising, a mop having a frame, a pulley secured on said frame, a mop handle pivotally secured to the frame, an actuating member slidably mounted relative to the handle, a pulley mounted in the handle, and a flexible member engaged with and passing around the pulley on the frame and extending over the pulley in the handle and having its ends attached to the actuating member.

3. A device of the class described comprising, a mop having a frame, a housing pivotally mounted thereon, a mop handle secured to said housing, a pulley secured on the frame and located within the housing, an actuating member slidably mounted relative to the handle, a pulley mounted in the handle and a flexible cable extending around and secured to the pulley in the housing and extending over the pulley in the handle and having its ends attached to the actuating member.

4. A device of the class described comprising, a mop having a mopping surface on each of its two faces, said mop being pivotally mounted on a handle and formed with an opening to one side of the pivot permitting the mop to be swung on the pivot to bring either of its mopping surfaces to face the floor, mop shaking means comprising a rocking element on the mop and a manipulator movable on the handle and an actuating connection between the rocking element and manipulator, said shaking means rocking the mop through an arc of at least 180 degrees to bring either of the two mopping surfaces to face the floor.

5. A device of the class described comprising, a mop having a frame, a pulley secured on said frame, a recessed mop handle pivotally secured to the frame, a sleeve-like actuating member slidably mounted relative to the handle, a pulley mounted in the handle, and a flexible cable engaged with and passing around the pulley on the frame and extending through the recessed handle and over the pulley in the handle and having its ends attached to the actuating member.

6. A device of the class described, a mop having a frame, a housing pivotally mounted thereon, a mop handle secured in said housing and provided with two spaced and longitudinally ex-

5 tending recesses, a pulley secured on the frame and located within the housing, a sleeve slidably mounted relative to the handle, a pulley mounted in the handle above the sleeve, and a flexible cable extending around and secured to the pulley in the housing and extending upwardly within the recesses in the handle and over the pulley in the handle and having its opposite ends attached to the sleeve.

10 7. A device of the class described comprising a mop handle provided with a pair of longitudinally extending parallel grooves extending for part of the length of the handle, said handle having a recess at one end of the grooves in which a pulley is rotatably mounted, a flexible cable movable in the grooves and passing over the pulley, a sleeve slidably mounted on the handle over the grooves, and having the ends of the cable attached at the opposite ends of the sleeve, 15 a housing in which one end of the mop handle is fitted, a mop frame pivoted in the housing and a rocking member located within the housing and secured to the frame, said rocking member

being attached to the cable and engaging the same at two points laterally spaced from the mop frame pivot.

8. A device of the class described comprising, a reversible mop having two mopping surfaces on two of its opposite sides and adapted for use with either one of its two sides downwardly disposed, a recessed handle so pivoted to the mop that there is an opening in the mop to one side of the pivot and the mop may be swung on its pivot to bring either of its sides to face the floor, a slidable member mounted on the handle for reciprocation thereon, a rocking member secured to the mop, movable connecting means extending between the rocking member and slidable member by which the mop may be swung on its pivot through an arc of at least 180° by manual reciprocation of the slidable member regardless of which of the two sides of the mop is downwardly disposed, said movable connecting means 20 having parts disposed in and movable through the recessed handle.
